UNITED STATES PATENT OFFICE.

JAMES HENRY ORR, OF PHILADELPHIA, PENNSYLVANIA.

GARBAGE-RECEPTACLE.

1,360,569.

Specification of Letters Patent. Patented Nov. 30, 1920.

Application filed January 23, 1920. Serial No. 353,628.

To all whom it may concern:

Be it known that I, JAMES H. ORR, a subject of the Dominion of Canada, residing at Philadelphia, in the county of Philadelphia and State of Pennsylvania, have invented certain new and useful Improvements in Garbage-Receptacles, of which the following is a specification.

One object of my invention is to provide 10 an improved receptacle for garbage or other refuse and which can be readily attached to a fence adjacent a hole therein so that the receptacle can be tilted by a collector and the entire contents of the receptacle can be readily removed therefrom.

Another object is to make my invention 15 of a simple and durable construction and so that it can be quickly and cheaply manufactured.

These objects, and other advantageous ends 20 which will be described hereinafter, I attain in the following manner, reference being had to the accompanying drawings in which—

25 Figure 1 is a sectional elevation showing in full lines my improved receptacle in its normal position and in dotted lines the position of said receptacle having been tilted into a cleaning position,

30 Fig. 2 is an elevation looking in the direction of the arrow α , and

Fig. 3 is a transverse section taken on the line 3—3 of Fig. 1.

Referring to the drawings, 4 represents a 35 fence having a hole 5 therein and 6 represents a can or container which is hinged at 7 above its bottom to the fence 4. A lid 8 is hinged at 9 to an angle 10 which is secured to the inner surface of the fence 4 and 40 this lid normally closes the open top of the container 6.

A handle 11 is provided whereby the container can be swung on the hinge 7 outwardly through the hole 5. A spring detent 45 12 is secured to the angle 10 and engages the upper end of the handle 11 so as to prevent the container from accidentally swinging on its hinge. A plate or second bottom 13 is adapted to normally rest on the integral bottom 14 of the container 6; said plate slidably fitting within said container in the direction of its height so that in moving upwardly the peripheral edge of the plate 13 will always be positioned closely 55 adjacent the inner surface of the container. A rod 15 has its lower end secured to the

plate 13 and projects upwardly for a portion of its length in a vertical direction when the container is in its normal condition. The upper portion 16 of the rod 15 60 is preferably extended at a slant as illustrated in Fig. 1 and the extreme upper end of the rod 15 is provided with a handle 17. The plate 13 normally rests on the integral bottom 14 of the container 6 and any garbage or refuse is dumped into the container and rests upon the plate 13. To remove the garbage or refuse from the container, the latter is swung into the dotted position and the rod 15 is pulled by the handle 17 and 70 the plate 13 will be slid longitudinally of the container and in this manner the entire contents of the container can be readily removed.

By having the upper portion 16 of the rod 75 15 extend at a slant, it is an easy matter by a swinging movement of the arm for a collector to pull the plate 13 from the container.

While I have described my invention as 80 taking a particular form, it will be understood that the various parts of my invention may be changed without departing from the spirit thereof, and hence I do not limit myself to the precise construction set forth, but 85 consider that I am at liberty to make such changes and alterations as fairly come within the scope of the appended claim.

Having thus described my invention, what I claim as new and desire to secure by Letters Patent is:—

A receptacle of the character described including a hinged container having an opening at its top; a plate normally resting on the bottom of said container; and a rod 95 connected to said plate and having a portion extending toward the opening of the container whereby said plate can be conveniently pulled toward said opening to remove the contents of the container when the latter is in a tilted position, said rod having a portion extending at a slant to the axis of said plate when the container is in its normal and tilted condition; substantially as described.

In testimony whereof I have signed my name to this specification in the presence of two subscribing witnesses.

JAMES HENRY ORR.
